REFRIGERATED SHOWCASE

Filed Aug. 11, 1926

Fig. 1.

UNITED STATES PATENT OFFICE

KARL ALBERT WEBER, OF LOS ANGELES, CALIFORNIA, ASSIGNOR TO WEBER SHOW-CASE & FIXTURE COMPANY, OF LOS ANGELES, CALIFORNIA, A CORPORATION OF CALIFORNIA

REFRIGERATED SHOW CASE

Application filed August 11, 1926. Serial No. 128,573.

This invention relates to refrigerated showcases and is more particularly directed to a refrigerated showcase and means for maintaining within the showcase a uniform and 5 definite temperature through the interior thereof.

Many refrigerated showcases are now used for the display of meats and other articles of food which must be maintained at a low 10 temperature, if the same are to be displayed any considerable length of time, in order to preserve the same.

Many refrigerated showcases have been constructed and patented, but the principal 15 difficulty had with such showcases lies in the fact that there is not maintained throughout the showcase a uniform temperature. The upper shelves of such showcases will be at a temperature of from several to twenty or 20 more degrees higher than the lower shelves thereof so that the food upon the upper shelves is not properly cooled, or that upon the lower shelves is cooled to a temperature below that desired for the correct preservation 25 thereof.

It is therefore an object of this invention to provide a refrigerated showcase having means for maintaining throughout the showcase a uniform or substantially uniform temperature 30 so that the food positioned within the showcase for display will be properly preserved.

Another object of this invention is to provide a means for maintaining throughout the 35 showcase a substantially uniform temperature and which means is inexpensive to operate and automatic in control.

Another object of this invention is to provide a refrigerated show case having means 40 mounted therein for maintaining a uniform temperature throughout the case, and which means constitute a continuous coil extending substantially the length of the showcase and in which coil a circulating means is mounted 45 for circulating a cooling solution or brine through the coils.

Another object of this invention is to provide a refrigerated showcase having means 50 for maintaining within the showcase a uniform temperature, and which means comprise

a brine container which is insulated on its exterior from the interior of the show case and from which brine solution the cooled brine is circulated to a substantially horizontal coil mounted above the center line of the 55 container and which coil is of a continuous construction returning the brine to the container.

Another object of this invention is to provide a draft or air circulation control means 60 within the container for the control of circulation of air for maintaining the upper regions of the showcase at a temperature substantially uniform with that of the lower regions.

Other objects and advantages of this invention will be apparent from the following detailed description of a preferred embodiment thereof as illustrated in the accompanying drawings, in which drawings:

Figure 1 is an isometric view of a showcase embodying this invention.

Figure 2 is an end sectional view taken substantially through the center of the showcase.

Figure 3 is an enlarged fragmental sectional end view of the top portion of the brine container, illustrating the means for maintaining a circulation of the brine through the cooling coil.

Figure 4 is a fragmental end section illustrating the manner of construction of baffle plates for the control of air circulation within the showcase.

Figure 5 is a diagrammatic view of a cooling apparatus embodied in this invention.

In the preferred embodiment of this invention, illustrated in the accompanying drawings, 1 illustrates a showcase composed of insulated sides 2 and 3 connected with insulated bottom and top sections 4 and 5, respectively. The sections 2, 3, 4 and 5 are at their ends connected with insulated end sections 6. The sections 2, 3, 4, 5 and 6 may be of any desired or preferred construction, the construction, for example, as is illustrated in my copending application for refrigerated showcase, filed July 28, 1926, Serial No. 125,392. The sections 1 and 5 being of a transparent material, such as plate glass, so as to enable the contents within the case to be observed from the

65

100

exterior thereof. The side 3, which is herein illustrated as constituting the rear of the case, is preferably provided with a plurality of doors 7 so as to enable easy access to the interior of the case.

5 Mounted within the interior of the case 1 at substantially the center thereof is a container 8, which container 8 may be of any desired or preferred construction and provides a brine container in which a brine solution is maintained. In order to maintain the interior of the case 1 at a substantially uniform temperature, and in order to enable an accurate control of the temperature within the 10 case 1, I have found that the container 8 should be insulated or covered with an insulating material, such as illustrated at 9, so as to prevent the container 8 acting as a cooling member. The container 8 therefore, which 15 contains the cooling brine, acts merely as a container for the cooling brine or solution and does not act as a cooling member for cooling the interior of the container. It is therefore possible to employ within the container 20 8 a brine solution which is at a temperature materially below that desired within the case 1.

25 Means are provided for circulating the brine solution from the container 8 through a coil 10 which is mounted above the mid-section of the case 1, which means are preferably of the following construction:

The coil 10 is an endless coil which extends longitudinally of the case 1 from the container 8 substantially the length of the case 1. The ends 11 and 12 of the coil 10 are connected with the interior of the container 8. The end 11 is connected with a T 13 which is mounted within the container 8. The end 12 is connected in open communication with the interior of the container 8. The T 13 is connected, as illustrated at 14, with a stand pipe 15 which extends substantially to the bottom of the container 8 and is mounted 40 within an upwardly extending section 16 of less cross-section than the remainder of the container 8, which section 16 is preferably provided with an insulated cover 17 upon which cover 17 a motor 18 is mounted.

50 Secured to the cover 17 is a sleeve 19, which sleeve 19 may be secured to the cover 17 in any desirable or preferred manner and is herein illustrated as screw-threaded to a flange 20, upon which flange 20, the motor 18 rests and is secured. The shaft 21 of the motor 18 is secured to a propeller shaft 22 by any suitable or desirable means, as is well understood in the art. The propeller shaft 22 is provided at its lower end with a small blade 55 propeller 23 which is within the T 13 below the level 24 of the brine in the extension 16 of the container 8. The propeller 23 operates to force the brine solution from the container 8 through the coil 10 but does not have to 60 raise the brine solution to the coil 10 as the

same is mounted below the level of brine in the container 8 and it is therefore unnecessary to provide a stuffing box around the shaft 22 to prevent the raising of the brine through the sleeve 19 out of the container 8 and a very small motor 18 may be employed for circulating the brine through the coil 10.

65 Mounted on the leads of the coil 10 are longitudinally extending bars 25, upon which bars 25 display racks 26 are set, which display racks 26 may be in the nature of trays of any desired or preferred construction as is well understood in the art. The trays 26 carry the food to be displayed within the case 1.

70 Mounted below the coil 10 are brackets 27 which are similar longitudinally extending bars 28 which carry a second set of trays 29 upon which food may be mounted in the lower portion of the case 1. At the bottom 75 of the case 1 a container 30 of any desired or preferred construction is provided upon which food may be placed for display purposes.

78 Means are provided for maintaining the 80 brine within the container 8 at the desired temperature, which means may be of any desired or preferred construction and are herein illustrated as comprising a compressor 31 which is adapted to compress ammonia, carbon dioxide, sulphuric dioxide, or like gas, and circulate the same through a cooling coil or boiler head 32 around which the brine solution circulates. The boiler head 32 may be located exterior of the case 1 and may supply a plurality of such cases 1 or containers 8 with cold brine or the boiler head 32 may be located directly in the container 8 and be provided with compressed refrigerant gases from the compressor 31, as is well understood in the art. The compressor 31 is driven by an electric motor 33 or other suitable or desirable motor, the operation of which motor is controlled by a thermostat, (not shown), and which thermostat may be of any suitable or desirable construction as is well understood in the art and is customarily supplied with automatic refrigeration compressing machines as manufactured and sold for use in connection with soda fountains, show cases 85 and the like. The thermostat being provided for controlling the temperature to which the refrigerant is reduced by the compression thereof.

90 Means are provided within the case 1 for regulating and maintaining a regulated circulation of air within the case 1 so as to aid in the maintenance of a uniform temperature throughout the control of the case 1, which means are preferably of the following circulation:

95 Air circulation baffle plates 35 are mounted under the coil 10 and extend substantially through the length of the coil 10. The baffle plates 35 are secured at their forward ends to 100

brackets 36 which are secured to the bars 25 by any suitable or desirable means, such as illustrated at 37, the plates 35 being pivoted to the members 37 at pins 38. The plates 35 may be regulated in the inclined position so as to regulate or restrict the air circulation within the case 1. For this purpose, I have illustrated brackets 39 which are secured to the rear bar 25, and which brackets 39 are provided with a plurality of holes 40, any one of which are adapted to receive hooks 41 which are mounted in spaced relation along the rear of the plate 35 at pins 42. By positioning the hooks 41 in the proper holes 40, the air circulation within the case 1 may be regulated to maintain the desired temperature within the case 1.

Mounted above the container 8 intermediate the plates 35 is an intermediate baffle plate 42^a which overhangs at its edges 43 the ends of the baffle plates 35, and which plate 42^a, because of the limited space provided, is preferably mounted rigidly in position and is not adjustable.

Means may be provided for aiding the air circulation in the case 1 but which are not believed necessary in order to maintain an accurate temperature control throughout the case 1, which means preferably comprise a small fan 44 which is secured to the upper end of the shaft 21 of the motor 18. The fan 44 and motor 18 are enclosed in a case or housing 45 which has a screen 46 at its upper end.

The motor 18 is connected in the electric circuit with the thermostat 34 so that the same operates only when the temperature within the case rises above that predetermined temperature at which the same is set to complete the circuit to the motor 33. The temperature of the brine in the container 8 may be materially below that desired in the interior of the case 1 as the temperature of the brine within the tank 8 will not control the case temperature due to the insulation 9, but the amount of circulation of the brine will control the same.

Having fully described a preferred embodiment of my invention, it is to be understood that I do not wish to be limited to the exact details herein set forth, which may obviously be varied without departing from the spirit of my invention as set forth in the appended claims.

I claim:

1. In a refrigerated showcase, the combination of insulated sides, bottom, top and end sections forming an enclosed case, a plurality of doors at the rear of the case, a container mounted within the said case adapted to contain a brine solution, means for cooling the brine solution, means for insulating the said container on the exterior thereof from the interior of the said case, a circulating coil connected with the said container and extending longitudinally outward therefrom, and

means for circulating the brine solution from the container through the said coil.

2. In a refrigerated showcase, the combination of an enclosed case having doors for access to the interior thereof, a container mounted in the interior of the case adapted to contain a cooling solution, means for maintaining the cooling solution at a low temperature, a longitudinally extending endless coil connected with the said container, means mounted on a level with and within the said coil for directly circulating the brine through the said coil, and means for insulating the said container.

3. In a refrigerated showcase, the combination of an enclosed case having doors for access to the interior thereof, a container mounted in the case and adapted to contain a brine solution, means for maintaining the brine at a low temperature, means for insulating the said container from the interior of the said case, a longitudinally extending coil connected with the said container at its ends, means mounted on a level with and within the said coil for directly circulating the brine through the said coil, and baffle means mounted below the said coil for controlling the air circulation within the said container.

4. In a refrigerated showcase, the combination of an enclosed case having doors for access to the interior thereof, a container mounted in the case and adapted to contain a brine solution, means for insulating the said container from the interior of the said case, means for maintaining the brine at a low temperature, a longitudinally extending endless coil connected with the said container, means for circulating the brine solution through the said coil, and baffle means mounted below the said coil for controlling the air circulation within the said case.

5. In a refrigerated showcase, the combination of an enclosed case having doors for access to the interior thereof, a container mounted within the case and adapted to contain a brine solution, means for maintaining the brine at a low temperature, means for insulating the said container on the exterior thereof, a longitudinally outwardly extending endless coil connected with the said container at the ends thereof, and adjustable baffle means mounted within the said container for regulating the air circulation therein.

6. In a refrigerated showcase, the combination of an enclosed case having doors for access to the interior thereof, a container mounted in the interior of the case and adapted to contain a brine solution, means for maintaining the brine at a low temperature, a longitudinally extending endless coil connected with the said container at its ends, means for circulating the brine through the said coil, and adjustable maffle means mounted below the said coil in the said case for regulating the air circulation therein.

7. In a refrigerated showcase, the combination of an enclosed case having doors for access to the interior thereof, a container mounted in the interior of the case and adapted to contain a brine solution, a longitudinally extending endless coil connected at its ends with the said container, means mounted on a level with and within the said coil for directly circulating the brine from the said container through the said coil.

8. In a refrigerated showcase, the combination of an enclosed case, a container mounted in the interior of the case and adapted to contain a brine solution, means for maintaining the brine at a low temperature, a longitudinally extending endless coil connected with the said container at its ends, the inlet to said coil extending to a point near the bottom of the container, and means mounted in the said inlet on a level with the longitudinally extending portion thereof for circulating the brine through the said coil.

9. In a refrigerated showcase, the combination of an enclosed case having doors for access to the interior thereof, a container mounted in the interior of the case adapted to contain a cooling solution at a low temperature, a longitudinally extending endless coil connected with the said container at its ends, a cover for the said container, a motor mounted on the said cover, a propeller connected with the shaft of the said motor and extending into the said coil for directly circulating the brine through the said coil.

35 10. In a refrigerated showcase, the combination of an enclosed case having doors for access to the interior thereof, a container mounted in the interior of the case adapted to contain a cooling solution, means for maintaining the cooling solution at a low temperature, said means including a compressor, a motor for driving the compressor, a longitudinally extending endless coil connected at its ends with the said container, means mounted on a level with and within the said coil for directly circulating the brine through the said coil, an automatic thermostat mounted in the case, and means connecting the said circulating means with the said thermostat so that the operation of the said circulating means is controlled from the said thermostat.

11. In a refrigerated show case a combination of an enclosed case having doors for access to the interior thereof, a container mounted in the interior of the said case, said container being adapted to contain a cooling solution, means for maintaining the cooling solution at a low temperature, a cooling solution circulating coil connected with said container and a propeller mounted in the entrance end of said circulation coil for circulating the cooling solution through said coil.

12. In a refrigerated show case the combination of an enclosed case having doors for

access to the interior thereof, a container mounted in the interior of said case, said container being adapted to contain a cooling solution, means for maintaining the cooling solution at a low temperature, a cooling solution circulation coil connected at its ends with said container, means for circulating the brine solution from said container through the circulation coil and means mounted within said case for circulating the air in said case.

13. In a refrigerated show case the combination of an enclosed case having doors for access to the interior thereof, a container mounted in the interior of said case, said container being adapted to contain a cooling solution, means for maintaining the cooling solution at a low temperature, a cooling solution circulation coil mounted in the case and connected at its ends with said container, a propeller for driving the cooling solution through said coil, a fan for circulating air in said case, and means for driving said propeller and said fan.

Signed at Los Angeles, California, this 5th day of Aug., 1926.
